Patented Jan. 16, 1917.

Martin Zinn, Inventor
By his Attorney
Clifford L. Davis

UNITED STATES PATENT OFFICE.

MARTIN ZINN, OF NEW YORK, N. Y.

DESIGN FOR A FRAME FOR HAND-BAGS.

50,213.

Specification for Design.

Patented Jan. 16, 1917.

Application filed October 19, 1916. Serial No. 126,618. Term of patent 8½ years.

To all whom it may concern:

Be it known that I, MARTIN ZINN, a citizen of the United States, residing at New York city, in the county of New York and State of New York, have invented a new, original, and ornamental Design for a Frame for Hand-Bags, of which the following is a specification, reference being had to the accompanying drawing, forming part thereof.

The figure is a view in perspective of the frame of a hand bag, showing my new design of frame clasp used in conjunction therewith.

I claim:

The ornamental design for a frame for hand bags, as shown.

MARTIN ZINN.

Witnesses:

FRANK J. QUIGAN,
J. A. Rose.
